DESIGN FOR A COMBINED PEDESTAL AND HOUSING FOR VAPOR TREATMENT AP- PARATUS OR SIMILAR ARTICLE

John E. Kelley, Larchmont, N. Y.

Application November 5, 1936, Serial No. 65,704

Term of patent 7 years

To all whom it may concern:

Be it known that I, John E. Kelley, a citizen of the United States of America, residing in Larchmont, county of Westchester, State of New York, have invented a new, original, and ornamental Design for a Combined Pedestal and Housing for Vapor Treatment Apparatus or Similar Article, of which the following is a specification, reference being had to the accompanying drawing, forming part thereof.

Fig. 1 is a perspective view of a combined

pedestal and housing for vapor treatment apparatus, or similar article, showing my new design.

Fig. 2 is a side elevational view of the housing portion of the article shown in Fig. 1.

I claim:—

The ornamental design for a combined pedestal and housing for vapor treatment apparatus or similar article, substantially as shown and described.

JOHN E. KELLEY.
